UNITED STATES PATENT OFFICE

2,275,180

CLIPPER

Neil Holsclaw, Chicago, Ill., assignor of one-half
to Fred E. Sudlow, Rock Island, Ill.

Application June 12, 1940, Serial No. 340,125

9 Claims. (Cl. 30—208)

This invention relates to improvements in hair clipping devices; and the main object of my invention is to provide a clipper which shall be adapted for ready and accurate trim clipping of hair or bristles growing in the ears and nostrils. Further objects are to provide such clippers adapted to better facilitate trimming moustaches, beards and sideburns; to provide such a clipper of relatively small size and which cannot cut or irritate the skin; to provide a unitary clipper construction of this character which comprises a lower stationary member and a reciprocating upper member and each of the members having comblike side edges; and to provide a device of this character which shall be simple in construction and operation and relatively inexpensive to manufacture. A special object is to guard against occasion for plucking out nasal hairs by the roots and the possible consequence of dangerous infections.

Illustrative embodiments of this invention are shown in the accompanying drawings in which:

Figure 1 is a top plan view of my improved clipper approximating actual size.

Fig. 2 is an enlarged sectional view taken on the line 2—2 of Fig. 1.

Figs. 3 and 4 are enlarged sectional views taken on the lines 3—3 and 4—4, respectively, of Fig. 2.

Fig. 5 is a top plan view of a modified form of construction embodying my invention.

Fig. 6 is an enlarged longitudinal sectional view through the clipper of Fig. 5, shown partly broken away.

Figs. 7 and 8 are enlarged cross sectional views taken on the lines 7—7 and 8—8 of Fig. 6.

Fig. 9 is a greatly enlarged plan view of the blank, before folding but after punching, which forms the stationary member of the modified form of construction shown in Figs. 5 to 8 inclusive.

Figs. 10 and 11 are perspective views of the two forms described above but illustrating a manual operating means. These views are approximately the actual size of the clipper.

Fig. 12 is an enlarged cross-sectional view taken on the line 12—12 of Fig. 11.

Referring to the embodiment shown in Figs. 1 to 4, inclusive, the invention comprises a handle 1 having a power unit such as a motor or vibrator (not shown) of any well-known form, embodied therein, a lower stationary skin contacting member 2, and an upper movable cutter member 3.

The two members 2 and 3 are preferably constructed of a high grade of tempered steel and they are each provided with a comb comprising a series of slots 4 and 5 respectively, extending

inwardly from the free edges of said members to form teeth 6 and 7, respectively. The member 2 is provided with a tongue 8 which is adapted to be inserted in the aperture 9 located in the end of the handle 1, and secured therein by any suitable means such as by a set screw 10.

The cutter member 3 is also provided with an integrally formed tongue 11 adapted for insertion in the aperture 12 located in the end of handle 1. The apertures 9 and 12 both lie in the same vertical plane. The aperture 12 is only large enough to readily accommodate the tongue 11 and provide for a free fore-and-aft lengthwise movement of the tongue 11. The tongue 11 has an aperture 13 into which one end of the power shaft arm 14 is adapted to seat. The other end of the arm is connected to the motor or vibrator, not shown, located in the handle, for operation by the motor, so that as it is repeatedly vibrated by the motor, the upper member 3 is reciprocated against the stationary member 2.

The upper member 3 is also provided with an elongated slot 15 into which is placed a bearing or spacer block 16 having an aperture 17 through which the machine screw 18 is inserted for engagement into the threaded aperture 19 of the lower member 2. A bowed spring 20 is positioned on the block 16 and member 3, and held thereon by the bearing head 21 of set screw 18. As the spring 20 is bowed downwardly so that the free ends of the same bear against the upper surface of member 3 it can readily be apparent that the member 3 will be positioned on the member 2 at all times for cooperation therewith. As the slot 15 is longer than the length of the block 16 the member 3 is free to reciprocate against the member 2 at all times.

As will be seen from Fig. 3 of the drawings, the members 2 and 3 are arcuate-shaped in cross-section so that the outer ends of teeth 6—7 come to a point at the side edges of the members to provide suitable comb-like fingers into which the hair to be clipped may readily enter and be clipped by the reciprocating movement of member 3.

Referring to the embodiment shown in Figs. 5 to 9, the lower or stationary member 22 is formed from a blank and is punched or otherwise bent substantially in a U-shape with the bottom bulged outwardly and the side walls disposed substantially in a perpendicular plane as shown in cross-section in Figs. 7 and 8.

The upper or movable cutter member 23 is also bent in a substantially U-shape and is smaller in cross-sectional area than the member 22 as is apparent from Figs. 7 and 8. The member 23 is

adapted to be placed inside the side walls of the member 22 and held therebetween by bolt 24 which extends through apertures 25 in the side walls of member 22 and through the slots 26 in the side walls of member 23.

The members 22 and 23 are provided with tongue parts 27 and 28 respectively, which function in the same manner and are secured to the handle in the manner as tongues 8 and 11 of the embodiment shown in Figs. 1 to 4 inclusive. Each of the members 22 and 23 is provided with slots and teeth 29-30 and 31-32 respectively, and are identical in every respect with the teeth and slots 6-7 and 4-5 of members 2-3 respectively. The member 22 is also provided with several elongated slots 33 to substantially lighten the weight of the clipper.

In the embodiments shown in Figs. 10 and 11 the motor or vibrator illustrated in Figs. 1 and 5 is eliminated and a manual power means provided.

This manual power means consists of a pair of handle bars 34-35 each hingedly connected at 36-37 to an end block 38. The block 38 is provided with a slot 39 into which the tongue 27' is adapted to be inserted and secured therein by any suitable means such as a set screw 10', in the same manner as shown and described for attachment of the tongues 8 and 27 to the handle 1. The tongues 11' and 28' are especially elongated for use in the manually operated devices of Figs. 10 and 11 so that the free ends thereof may be inserted through the slots 12' and be pivotally or otherwise secured to one end of each of the links 40 of the handle bars 34-35 respectively. The other ends of links 40 are pivotally or otherwise secured to brackets 41 which are formed by striking out a portion of handle bars 34-35 and bending such portions inwardly at right angles thereto, as clearly shown in Figs. 10 and 11. A bearing 42 is provided on the block 38 and a cooperating bearing or collar 43 is secured to the tongue 28' adjacent the free end thereof. A compression spring 44 is placed around the tongue 28' and between the bearings 42-43.

It will be apparent that by applying inward pressure on the handle bars 34-35, the links 40 will tend to force the inner member 23' outwardly, away from the bearing block 38, thereby reciprocating the teeth thereof against the teeth of the stationary member 22'. Upon release of the pressure applied to the handles 34-35 the spring 44 will tend to return the member 23' to its starting position. The movement of the cutter member 23' need be only a small fraction of an inch because of the minuteness of the teeth and slots of the cutter and stationary members.

It is to be understood that the prime numbers applied to Fig. 10 correspond to like parts of the construction shown in Figs. 1 to 4 inclusive and the numerals not primed applied to Fig. 11 correspond to like numerals in Fig. 10.

Referring especially to Figs. 5 to 9, it is to be noted that the two shear members or cutters, are U-shaped in cross-section, one being fixed and the other slideable, and that they constitute substantially a pair of U-combs one embracing the other with their teeth disposed for mutual shear cutting.

It will be understood that some of the details set forth may be altered or omitted without departing from the spirit of the invention as defined by the following claims.

I claim:

1. In a device of the class described, an elongated handle, a power unit in said handle, stationary and movable cutter members extending longitudinally from one end of said handle said stationary member being removably secured to said end of said movable handle, said cutter member being operatively connected to said power unit, said power unit arranged to reciprocate said movable cutter member, and resilient means to secure said members in cooperative relationship with each other.

2. In a device of the class described, a handle, stationary and movable cutter members extending longitudinally from one end of said handle and both having a pair of free edges provided with a series of alternate teeth and slots extending inwardly from said free edges, means to removably secure and stationary member to said end of said handle, means for reciprocating said movable cutter member, and means to secure said members together in cooperative relationship with each other.

3. A clipper comprising a pair of U-comb cutters one embracing the other, and means to reciprocate one relative to the other.

4. A clipper comprising a pair of U-comb cutters one embracing the other, and means to reciprocate one relative to the other, said cutters each including a pair of parallel flat sides slotted to form shear teeth.

5. A clipper comprising a pair of U-comb cutters one embracing the other, and means to reciprocate one relative to the other, said cutters each including a pair of parallel flat sides slotted crosswise to form shear teeth.

6. In a device of the class described a stationary body, power means carried thereby, an elongated movable cutter member and an elongated stationary cutter member each extending longitudinally in parallel relation, the one from one end of said power means and the other from said body, and each having an elongated tongue for connection to said power means and body respectively, said power means being adapted and arranged to reciprocate said movable cutter member against said stationary cutter member, comb parts on each of said cutter members, the teeth of which lie in parallel planes, and means to secure said cutter members cooperatively.

7. A clipper comprising a stationary body, a pair of relatively movable comb cutters carried thereby, power means also carried by said body and detachably connected operatively to one of said cutters, the other of said cutters being affixed to said body, and means to hold said cutters in mutually effective cutting relation.

8. In a clipper, a pair of elongated U-comb cutters formed to nest embracing one within the other in lengthwise mutually slidable relation and with their four comb edges arranged co-directionally to form two clipper couples disposed in substantially parallel spaced planes.

9. In a clipper, a pair of elongated flattish comb cutters disposed face-to-face, one of which is slightly concave to assure mutual contact at the cutting edges, means to mutually reciprocate said cutters lengthwise, one of said cutters having a central perforatory slot disposed lengthwise thereof, and the other cutter having a guide-and-spacer block fixed centrally thereon and fitting in said slot, and an elongated leaf spring secured centrally thereof to said block with its ends bearing resiliently on the corresponding end portions of the slotted cutter.

NEIL HOLSCLOW.
